(57) CLAIM

The ornamental design for a figurine display mounting hook, as shown and described.

DESCRIPTION

FIG. 1 is a front elevational view of a figurine display mounting hook showing my novel design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a first perspective view of the figurine display mounting hook of the present invention; and,

FIG. 8 is a second perspective view of the figurine display mounting hook of the present invention, as shown in use with a figurine.

The broken lines shown in FIGS. 7-8 are for illustrative purposes only and form no part of the overall claimed design.
